Attorney

UNITED STATES PATENT OFFICE.

LEWIS A. AMIS, OF MUSKOGEE, OKLAHOMA.

SHAVING-CUP.

1,369,766.

Specification of Letters Patent.

Patented Mar. 1, 1921.

Application filed March 7, 1919, Serial No. 281,213. Renewed July 19, 1920. Serial No. 397,547.

To all whom it may concern:

Be it known that I, LEWIS A. AMIS, a citizen of the United States, residing at Muskogee, in the county of Muskogee and State of Oklahoma, have invented certain new and useful Improvements in Shaving-Cups; and I do declare the following to be a full, clear, and exact description of the invention, such as will enable others skilled in the art to 10 which it appertains to make and use the same, reference being had to the accompanying drawings, and to the letters and figures of reference marked thereon, which form a part of this specification.

15 This invention relates to shaving cups or mugs and one of the objects thereof is to provide an inexpensive, durable lather cup of such construction that it may be conveniently carried as part of a traveling kit and 20 which may be attached to a "shaving stick" so that the end of the soap will be received through an orifice in the cup to serve as a plug and also provide the saponifying agent to make the lather. Another object of the 25 invention is to so construct the cup that it may fit over the stick in such manner that the stick will form a standard or base for the cup.

The invention also contemplates a 30 provision of means for providing a shaving cup adapted to be supported upon the rim of a bracket, mug or other suitable receptacle so that it may be readily detachable therefrom.

35 In the drawings,

Figure I is a perspective view of a conventional type of shaving stick and case, showing the cup applied, parts of the cup being broken away to better illustrate its 40 construction, and

Fig. II is a detached fragmentary perspective view of a slightly modified form of cup.

Referring now to the drawings by numerals of reference:

45 1 designates a shaving stick base having a

detachable complementary member 2, which fits over the shaving stick 3 which may consist of any appropriate kind of soap. The shaving stick 3 is generally round and may fit through a conical bottom orifice 4 in the 50 bowl-shaped cup 5, the end 6 of the stick forming a bottom plug which closes the orifice 4 and presents a saponifying surface to the action of the brush when water is supplied in the cup whereby a lather can be 55 made in the usual manner.

The cup will generally consist of rubber or some similar material adapted to readily fit over the stick and grip the sides thereof so as to eliminate the danger of leaking. The 60 particular contour of the cup is immaterial but the form shown permits a detachable cup or ring to be made which can be readily cleaned after use and which may be conveniently carried in the kit of a traveler. 65

In Fig. II I have shown a slightly modified form of cup differentiating from the preferred form primarily in that it is provided with a circumferential bead or rim 7 around its perimeter which may rest upon 70 the edge of a bracket, mug or other suitable receptacle whereby it may be suitably supported and removably held thereon in an obvious manner.

Having thus described my invention, what 75 I claim as new therein, and desire to secure by Letters-Patent is:

As a new and complete article of manufacture, a shaving cup comprising a rubber bowl-shaped member having an orifice in 80 the bottom thereof to receive a detachable saponifying plug, the walls of the opening diverging from the top toward the bottom and adapted to resiliently engage the plug.

In testimony whereof I affix my signature. 85

LEWIS A. AMIS.
